TREATMENT TO OBTAIN ONCOSTASIS
 Thomas J. Bardos, Snyder, N.Y., assignor, by mesne assignments, to Armour Pharmaceutical Company, a corporation of Delaware
 No Drawing. Filed July 26, 1961, Ser. No. 126,867
 3 Claims. (Cl. 167—65)

This invention relates to treatment in which there is obtained inhibition of neoplastic growth in animal studies and more particularly to treatment to obtain oncostasis with competitive antagonists of thymine and thymidine and inhibitors of the folic acid coenzyme systems.

This patent application is in part a continuation of my copending application Serial No. 847,678, filed October 21, 1959, now abandoned.

The treatment of this invention involves administering to a creature afflicted with neoplastic growth at least one compound of the group consisting of competitive antagonists of thymine and thymidine and at least one inhibitor of the folic acid coenzyme system. The term "competitive antagonist" refers to an analog of a compound which serves as a metabolite in a biosynthetic phenomenon by competing with the metabolite and preventing its access to substrate, which antagonism can be reversed by introducing into the biosynthetic system the immediate reaction product of such metabolite. Thus, this analog is an antimetabolite. Moreover, it will be understood that a suitable antimetabolite should not become a substitute metabolite in the biosynthetic system by being capable of only temporary inhibition of DNA biosynthesis and by ultimately being incorporated into the reaction product.

Although this treatment may be practiced by introducing into the DNA biosynthetic system, concomitantly, at least one compound from each of the aforementioned groups thereof, better results can be achieved by the administration to such biosynthetic system of a composition including at least one compound of the group consisting of competitive antagonists for thymine and thymidine and at least one inhibitor of the folic acid coenzyme system.

Thus, at least one compound from each of these groups of reactants can be incorporated into a suitable vehicle, and the resulting composition may be introduced into a system in which there is active biosynthesis of DNA to accomplish the purposes of this invention.

One class of compounds which may be employed in this invention as the competitive antagonist of thymine or thymidine can be illustrated by the formulae:

wherein X is selected from the group consisting of

and S, wherein R1 is a monovalent organic radical selected

2

from the group consisting of amino, uracil and alkyl having less than 4 carbon atoms, and wherein R2 is selected from the group consisting of hydrogen, ribosyl and desoxyribosyl.

5 These compounds can be further characterized as being degradable to 5-mercaptopuracil by hydrolysis, dissociation, oxidation, reduction or transmethylation. That is, these compounds are convertible to 5-mercaptopuracil by reductive hydrolysis, which reaction refers to hydrolysis under reducing conditions. In a practical sense, these 10 compounds are characterized by being capable of degradation to 5-mercaptopuracil in aqueous solution having a pH of from 9 to 13 and containing one mole equivalent of glucose although more precise control is achieved at 15 a pH within the range of 9.5 to 10.5 and at a temperature of from 70 to 100°C. at atmospheric pressure. It will be understood that the degradation product obtained in this reaction is the alkali salt of 5-mercaptopuracil, and that such alkali salt may be converted to free 5-mercaptopuracil by acidification.

20 It will also be understood that 5-mercaptopuracil, i.e., the compound in the foregoing formulae on the left hand, in which R2 represents hydrogen and the riboside and deoxy riboside thereof, can be obtained in an alkaline 25 reaction medium as the alkali salt, and consequently that such alkali salts are deemed to be included in this class of compounds, i.e., wherein the hydrogen in the 5 position of the left hand formula represents a metal such as zinc, sodium, etc.

30 Although 5-mercaptopuracil and the riboside and deoxyriboside thereof represent especially desirable compounds for the purposes of this invention, there may also be employed those compounds having the left hand formula above in which the hydrogen in the 5 position is replaced 35 by chlorine. In addition, other compounds represented by the foregoing formulae which may be employed in this invention, are, as follows: 5-uracilylethylxanthate, i.e., wherein X represents

40 5-uracilyldisulfide, i.e., wherein X represents S; uracil-5-isothiouronium chloride, i.e., wherein X represents

45 and S-acetyl-5-mercaptopuracil, wherein X represents

50 It will be apparent that the utility of these compounds for the purposes of this invention is predicated on the analogous relationship of the 5-thio function of the molecule to thymine and thymidine, and thus the substituent 55 X in this formula is such that it is subject to cleavage in physiological systems. Consequently, it will be seen that the monovalent organic radical described in connection with the formulae is not functionally involved in the utilitarian aspects of this invention and that consequently there may be substituted thereon any monovalent 60 organic radical.

Certain of these thymine and thymidine antagonists, and the method of the preparation thereof, are described in the co-pending patent application of T. J. Bardos et al.,

Serial No. 578,197, filed April 16, 1956, and in my co-pending patent application Serial No. 772,721, filed November 10, 1958, both now abandoned.

The term "inhibitor of the folic acid coenzyme system" refers to an antagonist to active forms of folic acid, such as inhibitors of folic acid, tetrahydrofolic acid, folinic acid and cofactor F.

One class of compounds which may be employed in this invention as the inhibitor for the folic acid coenzyme system can be illustrated by the formulae:

wherein X is either an imine or an oxygen group, wherein R is an organic group having steric resemblance to a methyl radical, e.g. methyl, ethyl, or halogen, and wherein R' is either an alkyl or substituted alkyl radical. The compounds represented by Formulae A1 and A2 may contain either an imino or oxygen group attached at the 2 and 4 positions, but such compounds should contain at least one of such imino groups. Since the imino or oxygen group attached at the 2 and 4 positions of these formulae are in an enolizable form, it will be understood that these formulae represent also desmotropes of these compounds.

The compounds of the foregoing Formulae A1, A2 and B have been found to be antagonists of riboflavin, 40 as well as being inhibitors of the folic acid coenzyme system, especially in being antagonists for folic acid.

The class of compounds represented Formulae A1 and A2 are related to isoalloxazine. When R in such Formulae A1 and A2 is a methyl radical and X is an imino group, the class of compounds represented thereby may be designated as 2,4 - diimino - 2,4 - desoxy - 6,7 - dimethyl - 9 - substituted isoalloxazines. Further, when R' in Formulae A1 and A2 is a ribityl radical, the compound is 2,4 - diimino - 2,4 - desoxy riboflavin. Also, when R' in these formulae is methyl, the compound may be designated as 2,4 - diimino - 2,4 - desoxy lumiflavin. On the other hand, when X in Formulae A1 and A2 is a hydroxyl group, the compounds represented are the corresponding 2 - imino - 2 - desoxy - 6,7 - disubstituted - 9 - substituted isoalloxazine and 4 - imino - 2 - desoxy - 6,7 - di - substituted - 9 - substituted isoalloxazine, respectively, in which the substituents at the 6 and 7 positions are either methyl, ethyl or halogen. An especially desirable class of compounds results when the substituent represented by R' in Formulae A1 and A2 is an alkyl or substituted alkyl radical containing not more than 6 carbon atoms, and an especially desirable class of compounds results when R' is a methyl, ethyl, ribityl or ribosyl radical.

The class of compounds represented by Formulae A1 and A2 may be prepared by aminating a chlorinated riboflavin analog of the structure:

and

10 wherein X is either oxygen or a dichloro group, wherein R is a group having steric resemblance to a methyl radical, e.g., methyl, ethyl or halogen, and where R' is either an alkyl or a substituted alkyl radical. The steric configuration of the compounds represented by this formula

15 requires a distribution of 3 chlorine atoms between the 2 and 4 positions. Thus, either the 2 or 4 position may have a dichloro substituent. In the preferred practice of this method, riboflavin may be acetylated with acetic anhydride in a pyridine medium. The resulting tetra-

20 acetyl derivative of riboflavin may be chlorinated with phosphorus pentachloride in an appropriate solvent, such as phosphorus oxychloride, phosphorus trichloride, chloroform, etc. This chlorinated compound can be aminated with such ammonia reactants as alcoholic am-

25 monia, liquefied ammonia, concentrated aqueous ammonia, etc., and then de-acetylated to obtain the ribo- flavin analog. The chlorination of the tetracetyl derivative of riboflavin may be such as to produce either the 2 - chloro - 4 - oxy, 4 - chloro - 2 - oxy, or 2,4 - trichloro

30 compound. The respective chlorine derivative can be aminated and de-acetylated to produce the corresponding analog of riboflavin.

The compounds represented by Formula B may be described as analogs of alloxazine, and when X in such Formula B represents an imino group the resulting compounds may be termed 2,4-diimino-2,4-desoxy-6,7-di-substituted alloxazines, and when R is a methyl radical the compound is 2,4-diimino-2,4-desoxy lumichrome. Also, when X in Formula B is an oxygen atom the compounds represented thereby are 2-imino-2-desoxy-6,7-di-substituted alloxazines, and the corresponding 6,7-dimethyl compound is 2-imino-2-desoxy lumichrome.

These antagonists of both folic acid and riboflavin, and the preparation thereof, are described in T. J. Bardos and D. B. Olsen U.S. Patent No. 2,867,614.

Another class of inhibitors of the folic acid coenzyme system are the anti-folic acid compounds of which the most widely known member is aminopterin. Another example of this class of compounds is a methotrexate.

50 The concomitant and simultaneous utilization of these two classes of compounds in the inhibition of DNA biosynthesis is predicated upon a synergism in which inhibition is achieved with a concentration of a mixture of such compounds significantly less than that with which 55 such inhibition may be achieved with either compound alone. That is, 5-mercaptopuracil and derivatives thereof have been found to be relatively ineffective in certain DNA biosynthetic systems. On the other hand, 2,4-di-imino-6,7-dimethyl - 2,4 - deoxyalloxazine and derivatives 60 thereof and aminopterin, although effective in inhibiting certain DNA biosynthetic systems, are significantly increased in effectiveness in inhibiting DNA biosynthesis in combination with 5-mercaptopuracil and derivatives thereof. It is postulated that in certain DNA biosynthetic systems 65 there are alternative pathways for the production of DNA, and that a single compound may inhibit only one of these alternative pathways and DNA biosynthesis may continue through the alternative pathway. It is believed that the 2,4-diimino-6,7-dimethyl-2,4-deoxyalloxazine and derivatives thereof and aminopterin are effective in inhibiting the synthesis of DNA by one alternative pathway, while 5-mercaptopuracil and derivatives thereof are effective in inhibiting the biosynthesis of DNA by another 70 pathway. Consequently, the utility of this invention is 75 predicated upon the observed inhibition of DNA biosyn-

thesis by concomitant or combined introduction therein of at least one compound of the 2,4-diimino-6,7-dimethyl-2,4-deoxyalloxazine or aminopterin series and at least one compound of the 5-mercaptopuracil series.

Accordingly, it has been discovered that the concomitant and simultaneous administration of at least one of the thymine antagonists and at least one of the inhibitors of the folic acid coenzyme system to a creature afflicted with a neoplasm provides selective inhibition of neoplastic growth greater than can be achieved with a compound of either of these series alone. Consequently, treatment of this invention is useful in obtaining oncostasis in creatures.

It will be apparent that the treatment of this invention can be carried out by a concomitant or simultaneous administration of at least one of each of the two groups of compounds. That is, in the practice of this invention, there may be administered to a creature afflicted with neoplastic growth at least one of each of these two groups of compounds at different time intervals in the course of treatment. On the other hand, in practicing the treatment of this invention, it is preferred to employ a combination of at least one of each of these two groups of compounds administered simultaneously to a creature afflicted with neoplastic growth.

Thus, the practice of this invention may involve the utilization of one compound of each of the two groups in a pharmaceutical carrier such as normal saline, each administered at different time intervals in the course of treatment. However, as suggested hereinabove, it is preferred to employ a combination of at least one of each of these two groups of compounds in a single pharmaceutical carrier such as normal saline, and to administer the resulting composition to the creature afflicted with neoplastic growth.

This invention can be further illustrated by the following specific examples:

Example I

The following is a comparison of the effect on mouse sarcoma 180 by (1) 5-mercaptopuracil, (2) 2,4-diimino-6,7-dimethyl-2,4-deoxyalloxazine, and (3) a combination of the above compounds:

Groups of iCR/Ha Swiss male mice, 10 mice per group, were treated by the subcutaneous injection of 10×10^6 sarcoma 180 cells. Treatment with the foregoing compounds was started 24 hours after the injection of the sarcoma 180 cells, and such treatment was suspended after 7 days. The animals were sacrificed 14 days after the injection of sarcoma 180 cells, and the tumors thereof were weighed.

The results were as follows:

Treatment (mg./kg.)	No. Died	Mean Tumor Weight (mg.)
Control.....	0	2,602
1 (50).....	0	3,000
2 (25).....	0	934
1 (50) plus.....	2	684
2 (25).....		

The foregoing results demonstrate that whereas 5-mercaptopuracil has little or no effect in effecting the regression of sarcoma 180, and whereas 2,4-diimino-6,7-dimethyl-2,4-deoxyalloxazine does produce regression of sarcoma 180, the combination of 5-mercaptopuracil and 2,4-diimino-6,7-dimethyl-2,4-deoxyalloxazine provides a significant enhancement in the regression of sarcoma 180.

Example II

The following is a comparison of the effect on leukemia L1210 in DBA/2 mice by (1) 5-mercaptopuracil, (2) amethopterin, and (3) a combination of the above.

Groups of DBA/2 mice, 10 mice per group, were treated by the subcutaneous inoculation of 10×10^6 leukemia L1210 cells. Treatment was instituted by the

traperitoneal administration of the foregoing compounds 24 hours after the inoculation of the leukemia cells. This treatment was continued for five days. The mice were sacrificed 10 days after inoculation with the leukemia cells, and the tumors thereof were weighed.

The results were as follows:

	Treatment (mg./kg.)	No. Died	Mean Tumor Weight (mg.)	No. of Mice Without Tumor
10	Control.....	0	899.5	.....
15	1 (50).....	0	871	.....
	2 (1.5).....	0	712	.....
	1 (50) plus.....	0	630	.....
	2 (1.5).....			

The foregoing results demonstrate that whereas 5-mercaptopuracil had little or no effect in effecting the regression of leukemia L1210 tumors, and whereas amethopterin has a definite effect in bringing about regression of leukemia L1210 tumors, the combination of 5-mercaptopuracil and amethopterin provides significant regression of leukemia L1210 tumors.

Example III

The following comparison between (1) 5-mercaptopuracil, (2) amethopterin, and (3) a combination of the above was carried out in a manner similar to that of Example II, except that treatment was effected by the subcutaneous administration of such compounds.

	Treatment (mg./kg.)	No. Died	Mean Tumor Weight (mg.)	No. of Mice Without Tumor
35	Control.....	5	1,386	.....
40	1 (50).....	9	1,825	.....
	2 (0.5).....	0	1,285	.....
	2 (1).....	0	580	.....
	2 (1.5).....	0	305	1
	1 (50) plus.....	0	817	.....
	2 (0.5).....			
	1 (50) plus.....	0	332	1
	2 (1).....			
	1 (50) plus.....	0	204	5
	2 (1.5).....			

¹ Animals without tumors were not included in the group mean weight.

Example IV

The following is a comparison of the treatment of leukemia 4946S and 4946R in AKR mice with (1) 5-mercaptopuracil, (2) amethopterin, and (3) a combination of the above.

Groups of AKR mice, 10 mice per group, were treated by the subcutaneous inoculation of leukemia 4946S and 4946R cells. Treatment by the subcutaneous administration of the foregoing compounds was instituted 24 hours after inoculation of the leukemia cells. The treatment was continued for a period of 7 days. The survival time of the mice was recorded.

The results were as follows:

	Treatment (mg./kg.)	Mean Survival Time (Days)	
		4946S	4946R
65	Control.....	7	6
	1 (50).....	7.4	5.8
	2 (1.5).....	8	6.4
	1 (50) plus.....		
	2 (1.5).....	12	6.8

The foregoing results demonstrate that whereas either 5-mercaptopuracil or amethopterin have little or no effect in prolonging the survival time of mice afflicted with leukemias 4946S and 4946R, the combination of 5-mercaptopuracil and amethopterin significantly prolongs the survival time of mice afflicted with leukemia 4946S, but

little effect is obtained with such combination on leukemia 4946R.

It will be apparent in view of the foregoing that this composition is useful as an oncostatic agent.

While in the foregoing specification this invention has been described in considerable detail by reference to specific embodiments thereof, it will be apparent to those skilled in the art that this invention is susceptible to other embodiments and that many of the details can be varied widely, without departing from the basic concept and spirit of the invention.

I claim:

1. A composition in dosage unit form containing, as essential active ingredients, neoplastic growth inhibiting quantities of at least one compound having the formulae

and

wherein X is selected from the group consisting of

and S wherein R1 is a monovalent organic radical selected from the group consisting of amino, uracil and alkyl having less than 4 carbon atoms, and wherein R2 is selected

from the group consisting of hydrogen, ribosyl and deoxyribosyl; at least one compound having the formulae

(A)

(B)

10 wherein X is selected from the group consisting of oxygen and an imino group, wherein R is selected from the group consisting of methyl, ethyl and halogen, wherein R' is a radical of the group consisting of alkyl and hydroxylalkyl radicals, and wherein at least one X in Formula A is imino; and pharmaceutically acceptable excipients.

20 2. A composition in dosage unit form containing neoplastic growth inhibiting quantities of 5-mercaptopurine and 2,4-dimino-6,7-dimethyl-2,4-deoxyalloxazine as essential active ingredients, and pharmaceutically acceptable excipients.

25 3. A composition in dosage unit form containing neoplastic growth inhibiting quantities of 5-mercaptopurine and amethopterin as essential active ingredients, and pharmaceutically acceptable excipients.
